UNITED STATES PATENT OFFICE.

ORAMEL S. BICKFORD, OF GREENFIELD, MASSACHUSETTS.

MACHINE FOR FLUTING TWIST-DRILL BLANKS.

1,274,502.

Specification of Letters Patent. Patented Aug. 6, 1918.

Application filed March 12, 1917. Serial No. 154,099.

To all whom it may concern:

Be it known that I, ORAMEL S. BICKFORD, a citizen of the United States of America, residing in Greenfield, in the county of 5 Franklin and State of Massachusetts, have invented certain new and useful Improvements in Machines for Fluting Twist-Drill Blanks, of which the following is a specification.

10 This invention relates to improvements in machines for fluting twist drill blanks. The invention, broadly, comprises mechanism for feeding the blank forward toward the cutter or fluting member at practically a uniform rate of linear travel, also at varying 15 rates of rotation of the blank during the cutting or fluting operation, whereby the pitch or lead of the fluting grooves is varied from the cutting end of the drill toward its shank.

An object of the invention is to provide means for automatically reversing the blank carrying carriage at the extreme ends of its travel, said means including mechanism 25 for varying the rate of travel of the carriage. That is to say, during a part of the forward movement the carriage moves slowly and during the balance of the cycle of operation or movement of the carriage 30 it moves faster.

A further object of the invention is to provide means for automatically rotating the blank through 180 degrees after the first flute or groove has been cut, whereby 35 when the cutter begins to operate again, it will cut or flute the blank on the opposite side.

A further object of the invention is to provide means for automatically disengaging 40 the cutter from the blank after the spiral or fluted grooves have been completed. Further objects and nature of the invention will appear in the body of the specification and will be particularly pointed out 45 in the claims.

Referring to the drawings:

Figure 1 is a top plan view showing the drill blank held in place during the cutting operation, also the means for imparting a rotative movement to the blank simultaneously with the forward movement thereof, and the trip mechanism for automatically disengaging the rotative mechanism from the spindle carrying the drill blank; 50

55 Fig. 2 is a side elevational view of Fig. 1, showing the means for vertically adjusting

the table also the mechanism which imparts a rotative movement to the blank, and the cam device by means of which the lead or pitch of the groove being cut in the blank 60 is varied;

Fig. 3 is a vertical sectional view on the line 3—3 of Fig. 1, showing the mechanism by means of which the head stock is operated and the mechanism by means of which 65 the angular elevation of the same is varied, also the mechanism by means of which the driving mechanism for the head stock is automatically disengaged at the end of the cutting operation; 70

Fig. 4 is a detail side elevational view of the automatic means for varying the lead or pitch of the groove in the blank as it is being cut;

Fig. 5 is a detailed view of the inclined 75 groove constructed that is attached to the lever mechanism for lowering the carriage to disengage a cutter at the end of the stroke or travel;

Fig. 6 is a view of the index device by 80 means of which the drill blank is permitted to rotate about its axis during the cutting operation when the clutch is in engagement;

Fig. 7 is a detail view showing the two 85 positions of the drill during the cutting operation and after the same is completed and moved away from the cutter;

Fig. 8 is a side elevational view of the opposite side of the machine from that shown in Fig. 2 and illustrating the mechanism 90 for moving the carriage back and forth, also the trip mechanism for automatically changing the speed of the movement of the carriage during its travel, also showing the train of gearing between the driving pulleys and the worm shaft which extends longitudinally of the machine from which the various operations of the machine are driven. 95

Fig. 9 is a detail view of the bushing through which the drill blank slides while 100 being cut;

Fig. 10 is a detail view of one end of the adjusting lever.

Referring to the drawings in detail: The base portion of the machine is indicated at 105 1 and secured to this portion are the upright standards 2 which carry the cutter shaft 3 to which the cutter 4 is secured. Secured to the cutter shaft is the cone driving pulley 5 designed to be belted to any suitable source of motive power. 6 designates the train of interchangeable gearing which 110

is interposed between the driving shaft 3 and the worm shaft 7. 8 and 9 are two beveled gears which mesh with the idle bevel gear 10. The gear 10 is secured to a 5 fixed shaft or stud 11 which passes downward through the base portion of the machine as shown in Fig. 3. The worm shaft 7 is mounted in bearings which are mounted on the movable plate 12. This plate is 10 adapted to be moved about the fixed stud 11 as a center for the purpose of varying the angular relation between the cutter spindle 3 and the axis of the drill blank. The plate 12 is clamped in rigid position by 15 means of the bolt and nut construction shown at 13 and which moves in the slot 13'. It should be mentioned that the axis of the stud or bolt 11 must necessarily pass upward and intersect the center or axial line of the 20 cutter spindle 3. A movable head stock 14 supports the drill blank. The bushing 15 (see Fig. 9) through which the drill blank, indicated at 16, passes when the blank is being fluted or grooved is supported on an 25 adjustable table 19. This blank is held in the chuck 17, the spindle of which passes through the bearing 18, which is also a part of 14, referred to later, which is mounted on the adjustable plate or table 19. 30 20 designates the spindle which drives the chuck and on the inner end of which is loosely mounted a gear 21 having attached thereto a clutch plate 22. Interengaging with this plate is another clutch plate 23. 35 These two plates are formed with two projections and recesses respectively which serve to cause the spindle 20 to be rotated about its axis simultaneously with the forward movement of the head stock 14. 40 Spaced from the plate 23 is an integrally connected plate 24 and located between the plates 23 and 24 is the shift fork 25 which is secured to the rock shaft 26. Attached to the end of this shaft is the arm 27 and 45 pivotally attached to this arm is a pawl 28. This pawl is designed to engage at its lower end with a pin 29 which is carried by the adjustable plate 30 for the purpose of separating the clutch plates 22 and 23 when the 50 head stock 14 returns to its initial position toward the left. The plates 23 and 24 are slidably mounted on the spindle 20 which is driven by means of a key connection between the hub 24' and the spindle. To the 55 end of the spindle 20 is secured a disk 31. Interposed between this disk and the slideable plates 23 and 24 and their integral hub 24' is a coiled compression spring 32, the purpose of which is to normally hold the 60 plates 22 and 23 together. Secured to the bearing block 18 is a stud 33 on which is mounted spur gear 34 and connected to this gear is a bevel gear 35 which in turn meshes with the bevel gear 36 that is rotatably 65 mounted on the stud 37, also secured to the bearing block 18. Attached to the outer-face of the gear 36 is a plate 38 (see Fig. 4) by means of the screws 39. Carried by the plate 38 is a threaded rod 40 which is mounted for rotation on the plate 38 and is 70 adapted to be rotated by means of the milled head 41. The lower end of this threaded rod 40 carries a roller 42 or other device which is located in the groove 43 of the angular shaped cam block 44. The groove 43 75 intersects the groove 45. The upper ends of the grooves 43 and 45 are shown in plan view in Fig. 1. The gear 36 is rotated as the head stock 14 is moved forward and backward by reason of the connection between 80 the roller 42 and the groove 43 in the adjustable cam block 44, which rotation of the gear 36 is transmitted through the pinion 35, gear 34, and pinion 21 to the clutch plates 22 and 23 and spindle 20 which in 85 turn rotates the drill blank 16 about its axis simultaneously with the movements of the head stock 14 either forward or backward, whereby a spiral flute or groove is cut in the blank by the cutter on the forward 90 movement of the blank. It should be stated that the block 44 having the grooves 43 and 45 therein is adjustably secured to the fixed support 46 which is formed with graduations 47 on the curved 95 edge 48 (see Fig. 1). This block is formed with a slot 49 to receive a clamping bolt 50 for the purpose of adjustably securing the cam block 44 in different positions of adjustment. The cam block 44 is pivotally secured to the frame of the machine by means of the angle iron 51, the arms 51' and 52 of which being connected to the plate 46 by means of the bolts 53 and 54. It will, therefore, be seen that as the head stock 14 100 moves backward or forward carrying the plate 38 with it, that the gear 36, by reason of the slidable connection between roller 42, and the inclined groove 43 in the cam block 44 will be rotated on its pivotal stud 37, 105 which in turn will, as previously stated, rotate the drill blank about its axis. The rate at which the gear 36 is rotated will of course determine the lead or pitch of the flute or groove which is cut in the drill blank. This 110 rate is determined by setting the cam block 44 in different positions of adjustment with relation to the fixed block 46. The head stock 14 is mounted on a vertically adjustable table 19, the forward end of this table 115 is connected by means of a link 55 to the middle point of a lever 56 that is movable around the pin or stud 57 for adjusting the angular position of the table 19 which determines the depth of fluting of the drill 120 blank. The forward end of the lever 56 is adjustable by means of the screw 58 and held in position by means of the graduated clamping nut 59, shown in Fig. 2. The other 125 end of the lever 56 is automatically moved 130

by means of an inclined slot construction shown at 60. Interposed between upright 12' of the machine and slide 62 is a spring 61. Mounted in a transverse opening 63 in 5 the lever 56 is a block 64 which block is formed with a semi-cylindrical projection 65. This block is adjustably retained in place in the lever 56 by means of the two set screws 66 for varying the position of 10 the block 64 in the lever 56. The inclined slot 60 previously referred to intersects the slot 67. The slide 62 carries the roller 69 which is held against the face of the cam 70 by means of the spring 61. This cam is 15 formed with a concentric surface 71 and a let-on and let-off portion 72 and 73, respectively. Located in the inclined slot 60 is a pin 74 which is attached to the slide 62 and is adapted to be moved up this incline 20 60 by the cam wheel 70, whereby this end of the lever 56 will be moved downward and is for the purpose of gradually moving the drill blank downwardly from the cutter, as shown in Fig. 7, while the flute in the blank 25 is being cut the desired depth and length during which time the head stock 14 is moved to its forward position toward the right hand end of the machine.

The cam 70 is operated from the cone driving pulleys 5 through the bevel gears 8 and 9 and 10 and the worm shaft 7. On this shaft is formed the worm 75 which meshes with the worm gear 76 that in turn operates the cam 70. This gear through the crank 30 wheel 82 moves the head stock 14 forward and backward, the speed of rotation being automatically changed as will be described in connection with the construction shown in Fig. 8, wherein the head stock 14 is connected to a link 77 which in turn is connected to a link 78 that is pivoted to the frame at 35 79. Mounted in the opening 80 of this link is a slide block 81 which block is adjustably connected to the crank wheel 35 82. The crank wheel 82 is located on the same shaft as the gear wheel 90 (see Fig. 3) and is operable from the gears 39 and 90. The extent of travel of the head stock can, therefore, be varied by varying 40 the position of the block 81 in the opening 80 of the link 78 and in the slot 83' of the crank wheel. The crank wheel is provided with the trip dogs 83 and also with a slot 83' to receive the head of the bolt for 45 adjustably securing the block 81 in the slot 80 of the link 78. These dogs can be placed in different positions of adjustment by means of the recesses 84 and set screws 84', and, as the crank wheel 82 rotates these dogs 50 engage the pin 85, which is mounted on or connected to a lever 86, which is pivoted at the point 85' and the lever 87 that controls the operation of the set of differential gearing and clutches in the box 87' so as to 55 change the rate of motion of the head stock 60

14 from the high to the low speed and vice versa, whereby a slow speed forward can be given to the head stock 14 and a quick return on the reverse movement of the head stock. It is to be understood that the construction of the differential gearing in the box 87', which is controlled by the levers 86 and 87 is a well known structure and does not form any part of the present invention 70 and is merely illustrative of the means employed to carry out a definite result, viz., to obtain a slow speed forward and a fast speed rearward. Secured to the shaft 88 is a pinion 89 (see Fig. 3) which meshes with the gear 90. The diameters of the gears 89 and 90 are in the ratio of two to one, respectively. Carried by the gear 90 is a pin 91 which pin is designed to engage the lever 92 and move the same away from the pin 93 which is mounted on the worm shaft supporting 75 box 7' in which is located worm shaft 7, this pin enters the recess 94 when the worm shaft 7 is elevated by hand. This shaft 7 drops aided by spring tension (not shown) and disengages the gears 75 and 76 80 from each other when the pin 91 strikes the lever 92. This operation takes place when the flutes or grooves in the opposite sides of the drill have been completed and the machine then comes to a standstill, as readily 85 understood. The worm shaft 7 moves about the pivot 8' as teeth 75 and 76 are disengaged when the pin 91 moves the lever 92 away. After a new drill has been inserted 90 by the operator then raises the worm shaft 7 100 by means of the handle 95 and the machine is again set in motion as soon as the gears 75 and 76 mesh.

The operation as a whole may be described as follows: Consider a drill blank 16 to be 105 inserted in and secured in the chuck 17. The head stock, being in the position shown in Figs. 1 and 2, is moved forward toward the cutter 4 through the connections between the cone pulley 5 and the head stock. 110 As the head stock 14 is moved forward through the link connections 77 and 78 the angular shaped cam block 44 is simultaneously and automatically imparting a rotary movement to the drill blank which determines the pitch or lead of the flutes or 115 grooves. When the cutter 4 commences the cut the roller 69 is at the bottom of the let-off portion 73 of the cam wheel 70. As the roller 69 passes over the eccentric surface 70' the lever 56 through the link 55 causes the table 19 to be gradually moved downward since the pin 74 on the slide 62 travels up the slightly inclined slot 67 in the block 64, and, when the roller 69 passes up 120 the shoulder 72 onto the concentric surface 71 of the cam 70, the pin 74 travels quickly up the sharply inclined slot 60 of the block 64 at which time the drill blank 16 is then 125 completely drawn away from the cutter as 130

shown by the dotted line 16' in Fig. 7. During the time the roller 69 is passing over the concentric surface 71 of the cam 70 the head stock 14 is moved to the end of its travel at the left hand end of the machine and forward again to its initial position shown in Figs. 1 and 2. The speed of this return movement is effected through the trip blocks 83 on the crank wheel 82 which engage the projection 85 on the lever 86 which is pivotally attached to the top of the differential gear case 87 at 85'. 87 is a lever which controls the clutch and differential gears in the gear case 87'. Meanwhile, during the last part of the movement of the head stock 14 to its rearward position and after the drill blank is withdrawn from the bushing 15 the drill blank 16 is automatically held from being rotated since the clutch plates 22 and 23 are now separated after having been rotated to produce one groove or flute, during the cutting of one flute by means of the connection between the gear wheel 36 and the pinion 21 on the spindle 20. That is to say the pitch of the flute extends through 180° from beginning to end. The clutch plates 22 and 23 are, during this last part of the return movement, disengaged by means of the trip finger engaging the pin 29. When the head stock 14 reaches the end of its rearward travel the trip finger 28 is then spaced away or is disengaged from contact with the pin 29, permitting the spring 32 to again move the clutch plates 22 and 23 together in order that the drill blank may be rotated through 180 degrees as the head stock moves forward again to its initial position shown in Figs. 1 and 2. The cutting or grooving operation now takes place on the opposite side of the drill blank as the head stock makes its second forward movement. It being understood that the roller 69 starts again at the bottom of the let-off shoulder 73 of the cam wheel 70. This operation continues until the drill blank is formed with the second flute or groove. The gear wheel 89 and cam 70 have now made two complete revolutions to one of the gear 90, at which time, or period, the worm shaft 7 is disengaged by the pin 91 engaging the lever 92 allowing this shaft to fall whereby the machine comes to a standstill and is ready to have the finished drill removed and a new one inserted. To start the machine again the operator has only to lift the handle 95 which throws the gears 75 and 76 together.

It may be stated in the interest of clearness of operation, that as the drill blank 16 backs out of the bushing 15 (Fig. 9) on the return movement of the headstock 14 it is revolving at the same rate of revolution as it enters this bushing; it continues this rotary motion until the forward end of the blank is free from possible contact with the cutter,

at which time the pawl 28 engages the pin 29 causing the clutch plates 22 and 23 to open and the rotation of the drill blank to cease. At the same time the blank revolving mechanism continues to rotate in a reverse direction through 180 degrees at which point the clutch plates 22 and 23 reengage or pick up the drill blank. By the time the blank again reaches the bushing 15 and the cutter 4 it has been revolved in a clockwise direction through 180 degrees, or, in other words the opposite side of the drill blank is now presented to the cutter on its opposite side having been revolved in a clockwise direction through 180 degrees from its position when it first entered the bushing.

It is to be understood that the pitch or lead of the flutes can be varied by varying the radial position of the roller 42 and the angular position of the cam block 44 about its pivot 53. As the head stock moves forward the finger 28 snaps over the pin 29 permitted by the spring 29' without operating the arm 27 which separates the clutch plates 22 and 23. On the return movement, however, of the head stock 14, when the same reaches a position in its travel to bring the finger 28 against the pin 29, the clutch plates 22 and 23 are automatically opened causing the reverse rotary motion of the drill blank to stop since the collar 24' is splined to the drill holding spindle, and, upon the separation of the plates 22 and 23 the drill blank is held stationary while the head stock completes the remainder of its rearward travel. After the first groove or flute has been cut in the drill blank 16, it is then backed out of the bushing 15 and away from the cutter 4 during the rearward travel of the head stock 14. Simultaneously with the rearward travel of the head stock the drill blank is rotated in the opposite direction from that during the cutting of the first flute or groove therein. This rearward motion or travel of the head stock and blank continues until the forward end or point of the blank is free from any possible contact with the cutter 4. When this position of the blank is reached, the pawl 28 then engages the pin 29 to open or separate the clutch-plates 22 and 23 from each other preventing further contra clockwise rotation of the blank. The drill-blank revolving mechanism including the gears 36, 25, 33 and 21 and the clutch plate 22 continues however, to operate, but the drill-blank can not be rotated since, as stated, the clutch plates 22 and 23 are now separated from each other. The plate 23 (see Fig. 6) is splined to the shaft 20 and when the clutch plates 22 are separated, rotation of this shaft ceases. On the return forward movement of the head stock, the clutch plates will reengage, being forced together by the spring 20. The pawl 28 idly snaps over the

pin 29 on the forward return movement and therefore permits the clutch to reengage. When the clutch plates reengage the shaft 20 is again revolved in a clockwise direction, and by the time the point of the drill blank reaches the cutter 4, the blank has been revolved so as to present its opposite side to the cutter to be fluted. Or, in other words, the blank has been rotated through 180 degrees in advance of its previous position when the first flute is cut, since the point of the drill blank was withdrawn from the cutter 4 and bushing 15. The blank is now fluted or grooved on its opposite side, and after the second cut has been made and the blank backed out of the bushing and away from the cutter the machine automatically stops when the finished drill can be removed. The pitch of each flute is, therefore, 180 degrees.

It will be seen from this description that this machine automatically produces a finished twist drill without the necessity of manual attention after the blank is inserted and the machine is started in operation.

What I claim is:

1. The combination in a twist-drill forming machine, of a base piece, a cutter rotatably supported thereon, means for clamping a drill blank in place, means for varying the angular relation both in a horizontal and vertical plane between the axis of the blank and the cutter, devices for automatically rotating the blank as the same is fed forward to the cutter, devices for automatically maintaining the drill blank against rotation during a portion of its travel as the same is moved in a rearward direction away from the cutter and to cause the blank to present the opposite side of the blank to the cutter on its next forward movement toward the cutter.

2. The combination in a machine for fluting or grooving twist-drill blanks, comprising a base piece, a cutter shaft, a cutter carried thereby, a head stock, a chuck carried by the head stock for securing the drill blank, means to adjust the angular relation between the axis of the drill blank and the axis of the cutter shaft, a cam plate, operative mechanism between said plate and the chuck to automatically rotate the drill blank about its axis during the forward movement of the head stock for varying the lead or pitch of the groove that is being cut in the blank, and means for automatically disconnecting said chuck and rotating means at a definite position during its travel in a reverse direction.

3. The combination in a machine for fluting or grooving twist drill blanks, comprising a base piece, a cutter shaft, a cutter carried thereby, a head stock, a chuck carried by the head stock for securing the drill blank, means to adjust the angular relation-

ship between the axis of the drill-blank and the axis of the cutter shaft, a cam block, operative mechanism between said block and the chuck to automatically rotate the drill blank about its axis during the forward movement of the head stock for varying the lead or pitch of the groove that is being cut in the blank, and means for automatically disconnecting said chuck and rotating means at the termination of the forward movement, 70 automatic trip devices to cause the head stock to move at a greater rate of motion during the return movement than during the forward movement while the blank is being fluted. 80

4. A twist drill machine, comprising a base member, a cutter supporting shaft mounted thereon, a plate movable on the base-member for varying the angular relation between the blank holding means and the cutter shaft, a worm shaft, bevel gear connections between the cutter shaft and the worm shaft to permit the plate to move on the base piece, a table on which the drill blank supporting devices are carried, a lever 90 connected to the table, means for lowering the table to vary the depth of cut of the flutes as the drill blank forming devices are moved forward toward the cutter, and means including a cam device on the lever for automatically moving the blank into a position that is free from the cutter at the termination of the cutting operation. 95

5. In a twist drill forming machine, the combination with a supporting base piece, 100 of a plate pivotally mounted thereon, a cutter supporting shaft, a cutter secured thereto, a head stock with means for rotatably securing the drill blank in place, means for moving the head stock toward the cutter, means to automatically cause the drill blank to be rotated about its axis simultaneously with the forward movement of the head stock, means to automatically rotate the drill blank through 180 degrees during a definite 105 part of the return movement of the head stock, and means to automatically disconnect the driving mechanism between the cutter and the head stock at the termination of the grooving or fluting operations. 115

6. A twist drill machine, comprising in combination with a base piece, a plate movably secured thereto, a single cutter shaft having a cutter secured thereto, a movable head stock, a chuck for securing the drill 120 blank and mounted on the plate, a table, an angular shaped cam plate secured thereto, a gear carried by the movable head stock, a threaded rod, a device on the gear having engagement with the cam block for moving the chuck, connecting mechanism between the gear and the spindle which drives the drill blank, a trip mechanism for automatically disengaging the connecting mechanism between the gear and the spindle at a fixed 125 130

- point in the return travel of the head stock, said mechanism remaining in separated position during the balance of the return movement of the head stock, said drill blank being automatically rotated so as to present the opposite side of the same to the cutter on its next forward movement, and means for automatically causing the connecting mechanism to reengage.
- 10 7. In a twist drill machine the combination with a base member, a plate on said member, a cam block pivotally secured thereto, a head stock, a link the pivotal center of which is offset from the center line thereof and attached to the base part of the machine, a second link connected to the opposite end of said link and to the head stock to cause the head stock to move, a crank wheel for operating the links, a cutter shaft, a cutter secured thereto, means for varying the angular relation between the cutter and the axis of the drill blank, means to rotatably support the drill in the head stock, means for automatically disengaging 25 and freeing the drill blank from the cutter at the end of each cutting operation, said means comprising a gear operated from the main shaft, a pivoted lever, a pin carried by the gear for engaging the lever, said lever having a shoulder portion which normally supports the worm shaft.
8. In a drill forming machine, the combination, a base-piece, a pivoted table secured thereto, means to permit movement 35 of the table on the base piece, a lever having connection with the table, a spring actuated slide on the lever, a cam formed with a let-on and a let-off shoulder portion, a concentric surface, and an eccentric surface, a 40 roller carried by the slide and engaging the cam, one end of the lever having an inclined slotted part engaged by the slide, whereby the end of the lever adjacent the cam will automatically lower the table as 45 said cam is operated to bring the cutter completely away from the cutter blank at the termination of the cutting operation.
9. In a drill forming machine, the combination, means for automatically imparting 50 a varying rotary motion to the drill blank as the same is fed toward the cutter to produce a flute or groove of varying pitch or lead, means for automatically stopping the rotary and forward motion of the blank 55 at a predetermined position when a flute in the blank has been cut the desired length, means for automatically stopping the rotation of the drill blank during a portion of

the rearward movement of the blank and while said drill rotating mechanism is 60 being operated to index, or position the blank for fluting the same on its opposite side on its next forward movement toward the cutter, and means to cause the drill blank rotating devices to be locked to the blank 65 after said indexing operation.

10. In a drill-forming machine, the combination, with a traveling head-stock having a chuck to hold a drill blank for rotation, a cam device for automatically rotating the 70 blank as the same and the head-stock is moved toward the cutter, means to hold the blank rotating means disengaged and the blank stationary during a portion of the travel of the blank in a rearward direction 75 away from the cutter, and until the head-stock starts forward again toward the cutter and has reached a predetermined position in its travel toward the cutter at which position the blank has been indexed or positioned for 80 cutting a flute on its opposite side, and means for reconnecting the blank rotating means to the chuck.

11. In a drill forming machine, the combination with a reciprocating head-stock, 85 a cutter, means on the head-stock for rotatably holding a drill blank, devices to impart a rotary motion to the blank as the same is moved toward and away from the cutter, said devices serving to reverse the 90 direction of rotation of the blank during the rearward travel of the blank away from the cutter for positioning said blank for cutting a groove on its opposite side during its next travel toward the cutter, means for 95 automatically maintaining the blank rotating means disengaged during a portion of the travel of the head-stock both away from and toward the cutter, during which portion the blank remains stationary, and means for 100 reconnecting the blank rotating means to the chuck, said blank being positioned with relation to the cutter to have a groove cut on the opposite side of the same as the blank engages the cutter the second time.

12. A drill fluting machine, comprising, in combination with a base piece, a head stock slidably mounted thereon, means for reciprocating the head stock, a rotatable chuck to receive the drill blank, an adjustable and angular shaped cam block secured to the frame work, operative means between said block and the rotatable chuck for varying the pitch of the fluting, and a cutter for forming the fluting.

ORAMEL S. BICKFORD.
